UNITED STATES PATENT OFFICE.

WORTHY CHANNING BUCKNAM, OF GENEVA, OHIO, ASSIGNOR TO
THE GENEVA AUTOMOBILE AND MANUFACTURING COMPANY,
OF GENEVA, OHIO, A CORPORATION OF OHIO.

PUMP-REGULATING MECHANISM.

SPECIFICATION forming part of Letters Patent No. 737,332, dated August 25, 1903.

Application filed March 28, 1902. Serial No. 100,452. (No model.)

To all whom it may concern:

Be it known that I, WORTHY CHANNING BUCKNAM, a citizen of the United States, residing at Geneva, in the county of Ashtabula 5 and State of Ohio, have invented a certain new and useful Improvement in Pump-Regulating Mechanism, of which the following is a full, clear, and exact description, reference being had to the accompanying drawings.

10 The object of this invention is to provide means for varying the delivery of a pump while it is in operation, so that it may supply fluid according to the varying demands upon it. My pump is especially designed for feeding 15 the water to the boiler of a steam-automobile, and the adjustable delivery, accomplished by the varying the stroke of the pump, obviates the necessity of by-pass valves to prevent the undue feeding of the boiler.

20 To this end the invention consists of a pump, mechanism for driving it, and means for varying the stroke of the pump while it is in operation. The particular embodiment of this, hereinafter shown and described, is also com- 25 prehended within my invention.

The drawings clearly illustrate my invention as applied to a pump suitable for automobile use, Figure 1 being a side elevation, and Fig. 2 a bottom plan.

30 In the drawings, A A represent a pair of pumps operated by the reciprocation of the common piston-rod B, which passes into the pump-chambers through stuffing-boxes C C, the pump-chambers being carried by the yoke 35 or frame D. The rod B, whose reciprocation causes the pumping action, has a collar b, from which project pins b'. These pins take into the bifurcated ends of the arms E, secured to a rock-shaft F. On the outer end

40 of the shaft is secured the lever G, the bifurcated end g of which is adapted to take around a pin (not shown) from some reciprocating part of the machinery—as the cross-head of the engine. The oscillation of the lever G thus causes operates the pump. Now I journal the rock-shaft F in a pair of levers H and H', which are secured to a shaft K, journaled

in the depending end d of the yoke-frame D. The arm H' is continued beyond the shaft K and there carries a nut J. This nut is swiv- 50 eled by having a shank j journaled in the arm H'. In this nut screws the upright rod L, carrying at its upper end an operating-handle N. By the rotation of the shaft L the lever H is swung, changing the position of the 55 rock-shaft F, and thus varying the stroke of the pump.

In operation when the engine is running, oscillating the lever G and driving the pump, if too much water is being delivered to the 60 boiler the handle N is turned in the direction to lower the nut J, thus bringing the rock-shaft F nearer the pins b' and shortening the 65 effective arm E, and thereby decreasing the stroke of the pump. If too little water is being delivered, the handle N is turned in the opposite direction, increasing the stroke of the pump. This governing of the delivery in no way interferes with the operation of the 70 pump and may be very conveniently accomplished during the running of the vehicle, as circumstances require.

I claim—

1. In combination, a frame, a pair of alined pumps carried thereby, a common piston-rod 75 for said pumps, a pair of links pivoted to said frame, a rock-shaft carried by the other ends of said links, one of said links being extended in the opposite direction from its pivot, thereby forming a lever, means engaging said lever 80 at the end thereof for shifting it to change the position of said rock-shaft, an arm carried by the rock-shaft and movably engaging a pin carried by the piston, and another arm carried by the rock-shaft for actuating the arm 85 first mentioned, substantially as described.

2. In combination, a frame, a pair of alined pumps carried thereby, a common piston-rod for said pumps, a pair of links pivoted to said frame, a rock-shaft carried by the other ends 90 of said links, one of said links being extended in the opposite direction from its pivot, thereby forming a lever, a nut loosely carried by the end thereof and provided with a threaded

opening, a screw rotatably mounted, for engaging said opening in said nut, an arm carried by the rock-shaft and movably engaging a pin carried by the piston, and another arm 5 rigid with said rock-shaft for actuating the arm first mentioned, substantially as described.

In testimony whereof I hereunto affix my signature in the presence of two witnesses.

WORTHY CHANNING BUCKNAM.
